(57)

CLAIM

The ornamental design for a wearable biosensing device, as shown and described.

DESCRIPTION

FIG. 1 is a perspective view of a wearable biosensing device;

FIG. 2 is another perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof; and,

FIG. 8 is a back view thereof.

The broken lines illustrate portions of the wearable biosensing device that form no part of the claimed design.

1 Claim, 8 Drawing Sheets
